FRAMER FOR RAFTERS

Robert L. Greve, Alhambra, Calif.

Application September 26, 1936, Serial No. 102,717

9 Claims. (Cl. 33—98)

This invention relates to devices for use in framing rafters. In Patent No. 2,004,318, granted to me on June 11, 1935, I have disclosed a device for the same purpose. My present invention is much simpler in its construction and more practical from a commercial point of view. Moreover, it is more compact, is more easily manipulated and is capable of uses for which my former invention was not readily adapted.

10: The principal objects of the present invention, therefore, are to simplify the construction of rafter framers, to cheapen their production, to render them more accurate, to simplify their use and to make their production an attractive and 15: profitable business undertaking.

As is well understood, the roofs of many buildings comprise rafters of various kinds, such as common, hip, valley and jack rafters. These, of course, must be accurately fitted together. All 20: are inclined in position. When the rafter extends between two parallel members, such as the common rafters which extend between the plate and ridge, the cut at the upper end must be vertical or plumb to fit against the ridge. If the rafter 25: extends between two members which are not parallel, as the jack rafters which extend from the plate to a hip rafter, the cut at the upper end must be not only vertical, but must be inclined to fit against the angularly positioned and inclined hip rafter. This is called a side cut. All 30: this, as stated, is well understood. But it is no simple matter to lay out the various rafters so that they will fit with precision into their intended places. The angles of the cuts vary in roofs, 35: depending upon the different pitches of the roof. Given the pitch of a roof to be framed, it is possible to adjust my invention in accordance with that pitch so that, with no subsequent change of adjustment, all of the rafters can be 40: cut with precision.

The accompanying drawing and the following specification disclose my invention in its present preferred form. It is realized, however, that the details of structure may be varied somewhat, 45: and it is, therefore, to be understood that the structure disclosed is merely an illustration of one practical embodiment of the invention and that the claims hereinafter made are not intended to be limited to the details disclosed any farther than the terms employed therein require.

50: In the drawing, Fig. 1 is a view of one side of the invention with the member attached for showing the lengths of the rafters required for the various pitches, showing one of the curved slots and indicating how the shape of said slot

is ascertained; Fig. 2 is a view of the opposite side of the invention, parts being broken away; Figs. 3, 4 and 5 are sectional views taken on lines 3—3, 4—4, and 5—5, respectively, of Fig. 1.

Referring to the drawing, 10 designates the stock. It is made up of a pair of elongated and parallel side plates 11 and 12. When assembled, they comprise a member which is rectangular in cross-section, as shown in Fig. 3, the plates being held in spaced relation by plugs or fillers 13 10 at their ends, the plugs being retained by screws 14 which extend through them and through the plates. Between these plugs, the stock is hollow and the side edges of the plates, which are preferably flanged inwardly, are spaced apart. Near 15 what will be termed its upper end, a pair of bolts or screws, 15 and 15^a, are extended through the stock and held in place, either by nuts, as shown, or by threading them into one of the plates. These screws are parallel and, preferably and as 20 shown, they are equidistant from the end of the stock. On the screw 15, between the side plates, is pivoted a blade 16, the upper marginal edge of which is turned to form a flange 17. The blade is held in proper position upon its pivot 25 screw by spacing sleeves 18 and 19 which surround the screw and engage with the blade and the side plates, as shown in Fig. 3. The side edges of the blade are straight and parallel so that either 30 can be employed as a straight-edge, as herein-after more fully explained. Preferably, however, the outer or flanged edge is used for that purpose.

Pivoted to the blade 16, at 20, is a link 21, the opposite end of which is pivoted to a movable 35 member 22 through a screw or rivet 23. (See Fig. 4). This member is, roughly, C-shaped with its main body within the hollow of the stock and its bent-out ends projecting into a slot 24 in the side member 11. The upper bent end of the 40 member not only enters the slot but projects through it to form an index marker or pointer 25 outside the stock. The member 22 is slidable in the slot and is adapted for locking in any set position by a thumb-screw 26 which is threaded 45 through the member and is projected through the slot, outside of which it is provided with a head 27. A washer 28 surrounds the screw between the head and the side plate and overlaps the side edges of the slot. Grasping the head 27, 50 the screw may be turned in one direction to loosen the member and then be moved laterally until the marker 25 is in its desired position, after which the member may be locked by turning the head in the opposite direction. 55

As has been stated, the pitch of the rafter varies in different buildings, depending upon the width and the rise of the roof. It is usually defined in terms of inches of rise per foot of run. To enable the index marker 25 to be set in accordance with different roof pitches, an index scale 29 is impressed on the stock alongside the slot 24, the graduations being numbered from zero on up in regular sequence, as shown. In Fig. 1, the marker is at the upper end of the slot and the pitch indicated is zero. When in that position, the blade 16 is at a right angle with respect to the stock. As the marker is moved down the slot, the angle of the blade is varied, as is obvious. Assuming that the marker is set at index number 7, the blade will stand in substantially the position indicated in dotted lines in Fig. 1, where there is also indicated, in dotted lines, a rafter R to which the invention is applied. When so applied, no matter where the index marker is set, a line drawn on the rafter along the edge of the blade will show where a common rafter is to be cut to give the plumb-cut at its upper end. If the length of the rafter be known, the bottom cut can readily be made, the same extending at a right angle to the plumb-cut. The length can, of course, be calculated or can be ascertained from tables giving the same for various pitches. I have, however, provided means for showing the length of the rafter required. It comprises a long blade 30 which is adapted to be slidably attached to the blade 16. On it is a scale 31, graduated in feet, extending from the center line of the latter blade. On the stock is another scale 32, also graduated in feet and extending from the center line of blade 16. The blades 16 and 30 are perpendicular to each other. When the index marker 25 is set at a certain pitch and the blade 16 is correspondingly moved, the blade 30 overlies the stock, as indicated in the dotted lines in Fig. 1, forming a right triangle, of which the stock is the hypotenuse. The run of the rafter being known, the blade 30 may be slid toward or from the stock until the mark of the scale 31 which indicates the length of the run falls upon the scale 32. The mark on the latter scale at the point of intersection of the scales will then give the rafter length. Thus, without calculation or recourse to some table, which may not be at hand, can the operator obtain the length of the rafter required for the given pitch and run. Moreover, having thus ascertained the length of the common rafter, he can move the framer to the ascertained position and, using the blade 30 as a straight edge, mark the rafter for the bottom cut. Having marked the rafter at both of its ends, it remains only to saw on the marked lines, moving the saw at a right angle to the plane of the side of the rafter.

As will be noted from Fig. 3, the blade 16 is located near the side member 11. Near the opposite side 12 and swinging parallel with the plane of movement of the blade 16 but in the opposite direction, is a blade 33. This blade is pivoted on the bolt or screw 15^a and is held from sliding thereon by spacing sleeves 18^a and 19^a. It, too, has a marginal flange 34, like the flange 17 of blade 16 except that it is turned in the opposite direction. The blade 33 is pivotally connected, by link 35, with an index pointer 36 through elements identical with those shown in Fig. 4. The pointer 36 is guided up and down the stock in a slot 37 in the plate 12, and is

held in any set position by a screw with a head 38, like the head 27 of the screw 26.

The blade 16 is intended for marking the plumb cuts of the common and jack rafters, while the blade 33 is intended for marking the plumb cuts of the hip and valley rafters. These rafters, of course, are longer than the common rafters for the same building and they have a different pitch. Consequently, the scale 38^a alongside the slot 37 is different from the scale 29. The length of the hip and valley rafters can be determined by applying the blade 30 to the blade 33 and by sliding it thereon until its scale 31 intersects a scale 39 on the plate 12 at a point representing on the scale 31 the length of the run of the rafter. That point of intersection gives, on the scale 39, the rafter length.

The jack, hip and valley rafters require side cutting at their upper ends, the jack rafters to fit against the vertical face of the inclined hip rafter and the inclined hip and valley rafters to fit against the vertical face of the ridge. In my invention the links 21 and 35 are adapted to serve as the side markers or straight-edges for marking for the side cuts of the respective rafters. That is to say, when the index pointer 25 is set to a pitch indicated by the proper mark on the scale 29 and the blade 16 is correspondingly swung, as indicated in dotted lines in Fig. 1, the link 21 has taken the position to serve as a straight edge for marking the side cut of the jack rafters. Further, when the index pointer 36 is also set to the same pitch, as indicated by the scale 38^a, and the blade 33 is swung, as in Fig. 2, to give the plumb-cut for the hip and valley rafters, the link 35 is positioned for marking the side cuts for these rafters. This result is made possible by forming the slots 24 and 31 in the double curved shape shown. In Fig. 1, I have indicated how the slot 24 and the scale 29 are laid out. With the blade 16 standing out from the stock at a right angle, there would be no pitch and the index pointer 25 should be in zero position. The slot 24 should, therefore start at some point in the arc of the circle about the pivot 20; and, since the slot must curve toward the far edge of the stock, as will be seen, the slot should start near the adjacent edge, the screw hole for the pivot pin 23 being at the center line of the slot. A series of positions are indicated for the pivot 20 as the blade is swung on its pivot 15. Now let the blade be moved to the position necessary for a pitch of 2 inches rise per foot of run. The pivot 20 will now be at the position designated 2^p. The screw hole for pin 23 must now be so positioned over the stock that the link 21 is at the proper angle for the side cut of the jack rafter, and a mark is made through said hole. The center line of the slot 24 must include that mark. The indicating mark "2" of the scale 29 is now impressed on the stock. The blade 16 is then swung to the angle corresponding to a pitch of three inches per foot, with the pivot 20 in the position indicated at 3^p. The end of the link is now swung until the angle of the link is correct for the side cut, and another mark is made through the screw hole in the end. That mark must lie in the center line of the slot. The index mark "3" is now made in the scale 29. In like manner, as many marks as may be necessary for definitely laying out the center line of the slot may be made; and, when so made, the slot 24 may be formed.

As will be seen from the numerous marks 2^p, 3^p, etc., and the lines connecting them with the 75

center line of the slot, the latter assumes the double-curve form as shown. The other slot 37 is laid out in the same manner.

It is believed that the foregoing is adequate to disclose the structure of my invention, the way in which the shapes of the slots are determined and the manner in which the invention is used. It will be understood that, given the pitch of a roof to be constructed, the index pointers are set to that pitch, as shown on the scales 29 and 38 and, in so doing, the blades and the links are positioned for laying out all the common, hip, valley and jack rafters required for that roof.

Having thus described my invention, I claim:

1. A device of the character described comprising a pair of parallel spaced side plates with means for holding them apart to produce a hollow stock member with open spaces between the edges of the plates, a pair of parallel pivot members extending transversely through the stock near one of its ends, a blade pivoted on one of said members and adapted to swing from an outer position to an inner position where it is housed within the stock, a scale impressed upon one of said side plates to designate roof pitches, an index member adapted for movement on the stock alongside said scale, a link connecting the said blade with said index member, the angles of the blade and link with the stock varying as the index member is moved and the blade and link being adapted to serve as markers for the plumb and side cuts, respectively of a jack rafter having the pitch for which the index member is set, a second blade pivoted on the other of said pivot members for swinging from an outer position to an inner position where it is housed within the stock, said second blade moving in a plane which is parallel with but is spaced from the plane of movement of the first mentioned blade, both of said blades pivoting from the same end of the stock member and lying side by side in said member when they are in closed position, a scale denoting pitches of hip and valley rafters impressed upon the other of the side plates of the stock, a second index member adapted for movement on the stock alongside the last mentioned scale, and a link connecting said second blade and said second index member, said second blade and its link being adapted for marking the plumb cut and side cut respectively of a hip or valley rafter having the pitch indicated by the second index member upon said second scale.

2. A device as set forth in claim 1 in which each of the side plates of the stock is provided with a slot by which the respective one of the index members is guided in its movements.

3. A device as set forth in claim 1 in which each of the side plates of the stock is provided with a double-curved slot by which the respective one of the index members is guided in its movement.

4. A device as set forth in claim 1 in which means are provided for indicating the length of common rafter required for a building having the pitch for which the first mentioned index member is set.

5. A device as set forth in claim 1 in which means are provided for indicating the lengths of the common, the hip and the valley rafters which are required for a building having the pitch for which the index members are set.

6. A device of the character described comprising a hollow stock member having opposed side plates, a blade pivoted in said member adjacent one end thereof and adapted to swing

from an outer position to an inner position where it is housed within the stock, a scale impressed upon one of said side plates to designate roof pitches, a curved slot in the said side plate extending alongside said scale, an index member 5 slidable in said slot, a link connecting said blade with said index member, the angles of the blade and link with the stock varying as the index member is moved in the curved slot and the blade and link being adapted to serve as markers for the plumb and side cuts, respectively, of a jack rafter having the pitch for which the index member is set, that side of the stock member having said slot being provided with a second scale extending along that margin from which the blade is adapted to be extended, and a second blade 10 having a scale thereon corresponding in its markings to the markings of said second scale, said second blade being adapted for attachment to the first-mentioned blade and being slidable 15 thereon toward and from the pivot of said first blade, the second blade extending at a right angle from the first blade and intersecting the said second scale where the first blade is in other than a right-angled position with the stock, the construction being such that when the second blade is moved until the point of intersection of its scale with the second scale corresponds on the scale of the second blade to the run of a rafter 20 said point of intersection will correspond on the second scale to the length of said rafter.

7. A device of the character described comprising a hollow stock member having opposed side plates, a blade pivoted in said member adjacent one end thereof and adapted to swing from an outer position to an inner position where it is housed within the stock, a scale impressed upon one of said plates to designate roof pitches, a curved slot in the said side plate extending alongside said scale, an index member slidable 25 in said slot, a link connecting said blade with said index member, the angles of the blade and link with the stock varying as the index member is moved in the curved slot and the blade and link being adapted to serve as markers for the plumb and side cuts, respectively of a jack rafter having the pitch for which the index member is set, that side of the stock member having said slot being provided with a second scale extending along that margin from which the blade is adapted to be extended, and a second blade having a scale thereon corresponding in its markings to the markings of said second scale, said second blade being adapted for attachment to the first mentioned blade and being slidable thereon toward and from the pivot of said second blade, the second blade extending at a right angle from the first blade and intersecting the said second scale when the first blade is in other than a right angled position with respect to the stock, for the purpose specified, a third blade pivoted in the stock adjacent the pivot of the first blade and adapted to swing from an outer to an inner position where it is housed within the stock, said third blade moving in a plane which is parallel with the plane of movement of the first blade but in direction opposed to the movements of the first blade, a scale denoting pitches of hip and valley rafters impressed upon the other of the side plates of the stock, said other side plate being provided with a curved slot alongside the last-mentioned scale, a second index member adapted for sliding movement within the latter curved slot, a link connecting said third blade and the second index member, said third blade 30

and its link being adapted for marking the plumb cut and side cut respectively of a hip or valley rafter having the pitch indicated by the position of the second index member upon the scale alongside the slot for that member, and a further scale at the marginal edge of the said other plate of the stock, the said second blade being adapted for connection with the said third blade to cooperate with the said further scale to show the length of the hip or valley rafter required by the setting of the second index member.

8. A device as set forth in claim 6 in which

the first blade is provided with an out-turned longitudinal flange and in which the second blade is provided with a transverse slot to receive the said flange.

9. A device as set forth in claim 7 in which the first and third blades are each provided with an out-turned longitudinal flange and in which the second blade is provided with a transverse slot to receive the flange of the blade to which said second blade is attached. 10

ROBERT L. GREVE.
